Primary Examiner—Martie Thompson

[57] **CLAIM**

The ornamental design for a hand held multi-functional devices in one housing including a stapler, staple remover, pencil sharpener, hole punch, tape measure, calculator, architectural and engineering scale, as shown and described.

DESCRIPTION

FIG. 1 is a perspective of hand-held, multi-functional devices in one housing including a stapler, staple remover, pencil sharpener, hole punch, calculator, tape measure, architectural and engineering scale showing our new design; FIG. 2 is a perspective view of the opposite side of FIG. 1; FIG. 3 is a perspective view rotated 90 degrees from FIG. 2, showing the pencil sharpener and stapler; FIG. 4 is a perspective view rotated 90 degrees from FIG. 1; FIG. 5 is a top view of FIGS. 1, 2, 3 and 4; FIG. 6 is a perspective view of FIG. 4 with the cover member open showing the calculator function; and, FIG. 7 is a bottom view of FIGS. 1, 2, 3 and 4.
